(57) **CLAIM**

The ornamental design for a tire sidewall, as shown and
described.

DESCRIPTION

FIG. 1 is a front view of a tire sidewall showing my new
design;

FIG. 2 is a rear view thereof;

FIG. 3 is a right side view thereof;

FIG. 4 is front perspective view thereof;

FIG. 5 is a fragmentary enlarged view showing the details of
the sidewall in FIG. 1;

FIG. 6 is a fragmentary enlarged view showing the details of
the sidewall in FIG. 5; and,

FIG. 7 is a cross-section view taken along line 7-7 in FIG.
6.

The dash-dot broken lines showing portions of the tire are
for the purpose of illustrating environmental structure and
form no part of the claimed design. The dash-dot broken
lines represent the boundary of the claimed design and no
part of the claimed design.
